PORTRABLE NAIL STRIPPER

Filed Oct. 1, 1928

Patented July 30, 1929.

1,722,820

UNITED STATES PATENT OFFICE.

FRED MURAKOSHI, OF SAN LEANDRO, CALIFORNIA.

PORTABLE NAIL STRIPPER.

Application filed October 1, 1928. Serial No. 309,455.

The invention forming the subject matter of this application relates to foldable nail strippers, and particularly to foldable devices which automatically arrange a bunch 5 of nails dropped thereon in single file, so that the same may be withdrawn by the carpenter using the nails to occupy the correct position between his fingers for immediate use.

The primary object of the invention is the 10 provision of a foldable nail stripper which is readily carried by a carpenter so that the same may be placed alongside the place where the carpenter works, and which may be readily set up into operative position and is supported in such a manner that each blow 15 struck by the carpenter with his hammer vibrates the supporting members on the whole nail stripper, thereby advancing the nails into the correct position, ready to be removed 20 for use by the carpenter.

Other objects of the invention are to provide a portable and foldable nail stripper that will be superior in point of simplicity, 25 inexpensiveness of construction, positiveness of operation and facility, convenience in use, and general efficiency.

In this specification, and the annexed drawing, the invention is illustrated in the form considered to be the best, but it is to be understood that the invention is not limited to 30 such form because it may be embodied in other forms; and it is also to be understood that in and by the claims following the description, it is desired to cover the invention 35 in whatsoever form it may be embodied.

In the drawing:

Figure 1 shows a perspective view of the nail stripper set up for use;

Figure 2 is a sectional view of the nail 40 stripper in a folded position inside of the casing in which it is carried;

Figure 3 is a fragmentary, detailed view 45 showing the manner in which the brackets of the nail stripper are supported so as to render the same portable at will; and

Figure 4 is a fragmentary view of the joint securing of the brackets to a support, showing the joint in the folded position of the bracket.

Referring to the accompanying drawing, 50 wherein similar reference characters designate similar parts thruout, the various figures described above adequately illustrate my invention, and the following detailed description is commensurate with the above 55 mentioned drawing in enabling an artisan to

construct and assemble the constituent parts of the same.

In carrying out my invention, the stripper is arranged in a case, denoted in its entirety by the numeral 1, which case is made in the form of a suit case and is made preferably of wood. The two halves 2 and 3 of the case 1 are hinged as at 4, and are provided with suitable catches 5 for closing the same. From the bottom 6 of the case rise two brackets 7, 60 the lower ends 8 of which are secured to the bottom 6 by means of bolts and nuts 9. A bolt 11 extends thru the upper end of each bracket 7. The brackets 7 are so formed that they incline toward the adjacent end wall of the case 70 1. To the upper ends of the brackets 7 are secured standards 12. The standards are so shaped that the lower portion thereof extends in extension of the brackets 7, and the uppermost portion thereof extends substantially vertically. In the lower end of each standard 12 is cut a square slot 13, which terminates toward the lower end of the standard 12 in a round aperture 14. It is to be noted that the portion of the bolt 11 which extends 80 thru the slot in the lower end of the standard 12 is provided with oppositely disposed flat surfaces 16, which surfaces are in parallelism with the direction in which the brackets 7 slope. 85

It is apparent that when the standards 12 are disposed in the manner shown in Figure 1, they lower by their own gravity so that the square slot 13 slides over the flat faces 16 of the bolt 11; thus the standards 12 are supported in an upright position and are prevented from pivotal movement upon the bolt 11. The standards are folded on this joint by pulling the standards 12 upwardly until the round aperture 14 is raised in a position 95 surrounding the bolt 11, whereupon the lower end of the bracket may be pivoted around the bolt 11 so as to assume the folded position within the case as shown in Figure 2.

To the upper ends of the standards 12 is secured a box 17 in the manner shown in Figure 1. The ends of the standards 12 are secured to the opposite sides of the box by means of bolts and nuts 18, the ends of the standards being spaced and reinforced by a 105 substantially U-shaped cross member 19, the legs of said U-shaped member 19 extending between the sides of the box 17 and the upper ends of the standards 12. The box 17 and the U-shaped member 19 are pivotally sup- 110

ported on the nuts and bolts 18 so that the same may be folded alongside the standards 12, whereby they are allowed to assume the position shown in Figure 2.

5 The lowermost end of the box 17 is open so that a bunch of nails thrown in the box will work downwardly, particularly when the standards 12 are set into slight swinging or vibrating motion by the handling of a hammer in the immediate vicinity. The box 17 is disposed at such a slant that the nails advance over the lower edge of the box, wherefrom they drop upon a guide 21, which guide consists of a plurality of V-shaped troughs 22 with open bottoms so as to form slots, allowing the shanks of the nails to drop therethru while preventing the heads from doing so.

10 The troughs 22 are arranged to slant downwardly from the lower end of the box in a reverse direction. The troughs communicate at their lower ends with sets of rods or rails 23 arranged so as to continue the slots in the troughs and to allow the heads of the nails to 15 ride downwardly therefrom. The upper end of the guide containing the troughs is secured to the lower end of the box by means of hooks 24 which are pivotally supported in the sides at the lower end of the box 17, and are so bent 20 as to be readily inserted in corresponding apertures in the upper end of the guide 21. The lower ends of the rods or rails 23 are fastened to a metal strip 26, the ends of 25 which are bent at right angles so as to form a U-shaped strip with comparatively short legs 27. The legs 27 are pivotally supported on the standards 12 by means of bolts and nuts 28. The folding of the guide member is performed by removing the hooks 24 from 30 the guide 21, thereby releasing the same so that the guide 21 drops by its own gravity, pivoted around the bolts and nuts 28 and assumes the position shown in Figure 2.

35 In the rods an offset 29 is formed near the joint with the troughs 22 in the manner described in my Patent #1,677,527, dated July 17, 1928. These offsets provide steps in the rods and allow nails suspended from the rods to be withdrawn therethru. In order to reinforce the structure without materially reducing its resiliency, the brace 19 carries a hook 31, while another hook 32 is secured in a co-acting position with the hook 31 on the outside face of the corresponding side of the 40 half 2 of the casing 1. A spring 33 is stretched between the hooks 31 and 32, the opposite ends thereof being removably supported on the hooks. A shield 34 is provided so as to be readily positioned opposite 45 the end of the rails 23 and outside of the standards 12 so as to prevent the accidental falling of the nails out of the case 1.

50 A guard rail 37 extends transversely over the rails 23, and is spaced therefrom so as to allow the passage of the nails thereunder.

The guard rail is formed from a wire bent in the manner shown in Figure 1, the end of the wire being fixedly secured to the metal strip 26.

55 In operation, the standards 12 extend in an upright position so that the square slot 13 thereof slides over the flat faces of the bolts 11, thereby being maintained in an upright position. The box 17 is then turned around the pivots 18, the slope of the box 17 60 being determined by the position of the upper edge of the guide 21. The guide 21 is turned around the bolts 28 until the ends of the hooks 24 are in cooperative position relative to the corresponding apertures in the guide 21. 65 When the hooks 24 are secured to the upper end of the guide 21, the slope of the box 17 and of the troughs 22 is determined thereby. Now, by securing the spring 33 upon the opposite hooks 31 and 32, the structure is 70 strengthened in its upright position. Then the shield 34 is placed behind the lower end of the brackets 12, and the device is ready for operation.

75 The device is used in the manner described in my aforesaid patent, the operator dropping a bunch of nails on the box 17, which nails are guided thru the troughs 22 and rails 23 and are disposed in a long line, depending on their heads from the lower rails 80 23. The whole line may be removed thru the loop formed at the offset 29.

85 When the device is not in use, it may be readily folded by first releasing the spring 90 33 and placing the same on the bottom of the half 2 of the casing 1, in the manner shown in Figure 2. Next, the shield 34 is removed and it will be placed in the upper half 3 of the casing 1 after the device is folded. The next step is the releasing of the hooks 24 and 95 the dropping of the side 21 to the bottom 6 of the half 2. A trough shield 36, which depends from the bottom of the box 17 over the V-shaped troughs 22, is pivotally secured to the bottom of the box 17, so that the same 100 may be folded over the bottom of the box 17. Then the box 17 is pivoted around the bolts 18 over the standards 12. The standards 12 are then raised until the round aperture 14 in the lower ends thereof surround the respective bolts 11, whereupon the standards 12 are 105 pivoted around the bolts 11 so that the box 17 may rest upon the guide 21. It is to be noted that the box 17 and the guide 21 are so proportioned that the guide 21 fits within 110 the box 17 when the device is folded. Now, the shield 34 is placed in a corner of the upper half 3 of the case 1 in the manner shown in Figure 2. In this position, the compact 115 unit is folded in the lower half of the box. Then, by closing the case 1, the same may be 120 readily closed by the hooks 5 and forms a portable, light case.

125 It will be recognized that a particularly facile and simple device is provided for strip- 130

ping nails, which device, while efficiently and readily operating when set up, also combines strength with facility of transportation. The device may be readily set up, and when 5 in position, it combines vibratory operation with a ruggedness of construction adapting the same for its use. The device does not require any careful adjustment and readily lends itself to effective application by the 10 labor ordinarily available.

I claim:

1. In a nail stripper, a case; standards supported on said case and being adapted to be pivoted from an upright position to a folded 15 position in the case; a box pivotally supported on the standards so as to be foldable alongside the standards; means for guiding nails discharged from the box into a vertical position, and for supporting the heads of the 20 nails; said means being pivotally secured to said standards below said box; and means for detachably securing the upper end of the guide to the lower end of the box, thereby maintaining the box and the guide in oppositely inclined positions, said guiding means 25 being adapted to fit within said box, when the stripper is folded.

2. In a nail stripper, standards; a box supported on the standards in an inclined position; an end of the box being open; a guide having troughs with open bottoms therein for guiding nails, said guide being inclined oppositely to the box, the upper end of the 30 guide being secured to the open end of the box in operative relation thereto; guide rails extending from the guide in continuation of said troughs, the free ends of said rails being secured to said standards; and a shield depending from the bottom of the 35 box, the lower edge of said shield conforming to the troughs in the guide so that the edge is spaced from the open bottom of the troughs, directing the nails therethru.

3. In a nail stripper, standards; a box supported on the standards in an inclined position; an end of the box being open; a guide having troughs with open bottoms therein for guiding nails, said guide being inclined oppositely to the box, the upper end of the guide 40 being secured to the open end of the box in operative relation thereto; guide rails extending from the guide in continuation of said troughs, the free ends of said rails being secured to said standards; a shield depending from the bottom of the box, the lower edge of 45 said shield conforming to the troughs in the guide so that the edge is spaced from the open bottom of the troughs, directing the nails therethru; and a guard rail disposed transversely to said guide rails and in spaced relation thereto.

4. In a portable nail stripper, a foldable case; brackets fixedly secured to the bottom of the case; standards extending in continuation 50 of the brackets, each standard having a slot

therein terminating in a round aperture adjacent to the lower end thereof; flat pivots in said bracket and extending thru said slots for maintaining the standards in upright position, said standards being made foldable 70 around said pivots by bringing said round apertures into registry with the respective pivots; a box having a closed and an open end; means on the closed end of the box for pivotally securing the same to the free ends 75 of said standards; said box being foldable over said standards so that the bottom thereof is positioned alongside the standards; a guide having troughs with open bottoms 80 therein for guiding the nails; rails in continuation of the guide for holding the nails, said rails being so formed as to allow the removal of the nails therefrom; a cross member pivotally securing the ends of the rails to the lower portion of the standards; and means 85 for detachably securing the upper end of the guide to the open end of the box, thereby holding said box and said guide in oppositely inclined positions so that the nails are discharged from the box to the guide; said box 90 guide being such as to allow the positioning of the former upon the latter when folded in said case.

5. In a portable nail stripper, a foldable case; brackets fixedly secured to the bottom of 95 the case; standards extending in continuation of the brackets, each standard having a slot therein terminating in a round aperture adjacent to the lower end thereof; flat pivots in said bracket and extending thru said slots for maintaining the standards in upright position, said standards being made foldable 100 around said pivots by bringing said round apertures into registry with the respective pivots; a box having a closed and an open 105 end; means on the closed end of the box for pivotally securing the same to the free ends of said standards; said box being foldable over said standards so that the bottom thereof is positioned alongside the standards; a guide having troughs with open bottoms 110 therein for guiding the nails; rails in continuation of the guide for holding the nails, said rails being so formed as to allow the removal of the nails therefrom; a cross member pivotally securing the ends of the rails to the lower portion of the standards; and means for detachably securing the upper end of the guide to the open end of the box, thereby holding 115 said box and said guide in oppositely inclined positions so that the nails are discharged from the box to the guide; and a shield depending from the bottom of the box over said troughs, the edge thereof being spaced from the open bottom of the troughs; 120 said shield being swingable over the bottom of the box, said guide fitting within said box when folded in said case.

6. In a portable nail stripper, a case; a lower half and an upper half of said case 130

pivotedly secured to each other; brackets fixedly secured to the bottom of the lower half of the case in an inclined position; standards extending in continuation of said brackets, each standard having a square slot therein, terminating in a round aperture adjacent to the lower end thereof; flattened pivots extending from said brackets thru said slots for maintaining the standards in upright position; said standards being foldable around said pivots by raising the ends of the standards so as to bring said round apertures in registry with the pivots; a box having an open end, the closed end thereof being pivotally secured to the upper ends of the standards; a guide having V-shaped troughs therein, with open bottoms; hooks on the open end of the box for detachably securing the adjacent end of the

guide to the open end of the box; guide rails extending from said guide in continuation of said troughs; a cross member pivotally secured between the lower portions of the guides and supporting the extremities of said rails thereat, thereby maintaining the guide in an inclined position below the box, when said hooks are secured thereto; said guide and said box being so dimensioned that said guide fits within said box when they are folded in the lower half of the case; and a trough-protecting shield pivotally depending from the bottom of the box over said troughs, said shield being foldable over the bottom of the box.

In testimony whereof I affix my signature.

FRED MURAKOSHI.
